[57] ABSTRACT

A bathing cap, a crown portion of which has a loose fit on the wearer's head and a marginal portion of which has a stretch fit around the wearer's head. An air seal is effected between the marginal edge portion and the wearer's head by an elastic inflatable tube which extends around inside the cap adjacent to the marginal edge portion. The inflatable tube and the crown portion are inflated by air filler tubes which are long enough to reach the wearer's mouth when the cap is being worn and which can thereafter be tied in a decorative knot.

BATHING CAP

BACKGROUND OF THE INVENTION

1. Field of the Invention

This invention relates to bathing caps and in particular to caps designed for wear by ladies having hairdos, such as the bouffant type.

2. Prior Art

Bathing caps have, conventionally, been so constructed as to have a tight snug fit on a wearer's head particularly at the marginal edge portion of the cap so as to reduce the likelihood of water entering the cap and wetting the wearer's hair. In caps in which the snug fit is obtained by tension alone the cap does not completely conform to the contour of the head, being stretched tightly across flat portions and protuberances and providing spaces between the edge portion and the head where it crosses depressions.

Caps have been designed with an inflatable tube extending around the marginal edge to obtain conformity with the head profile and thus attain a somewhat watertight fit. Caps of prior design although affording, in some cases adequate protection against water seepage, tend to compress the wearer's hair against the head this effectively ruining an expensive coiffure.

SUMMARY OF THE INVENTION

The present invention provides a bathing cap which provides an effective water seal to reduce the likelihood of water entering beneath the cap to wet the wearer's hair and which also provides a required looseness of fit over the wearer's crown so as to avoid damaging an expensive hair-do.

The bathing cap of the present invention has a crown portion formed of thin pliant resilient material of a size and shape to fit the wearer's head loosely, and a marginal edge portion which has a snug stretch fit around the wearer's head. An inflatable elastic tube is secured inside the cap at the marginal edge portion. Air filler tubes extend into the inflatable tube and the crown portion of the bathing cap to enable the inflatable tube and the crown portion to be inflated by the wearer when the cap is disposed on her head, the tubes being long enough to enable them to be tied together in a decorative bow.

A detailed description following related to drawings gives exemplification of preferred embodiment of the invention which, however, is capable of expression in a structure other than that particularly described and illustrated.

DESCRIPTION OF THE DRAWINGS

FIG. 1 is a side view of a bathing cap in accordance with the invention disposed on a wearer's head.

FIG. 2 is an enlarged sectional view taken on line 2-2 of FIG. 1.

DETAILED DESCRIPTION

Referring to the drawings, a bathing cap, generally 10 in accordance with the invention is shown fitted on a wearer's head 11. The cap is formed of a resilient pliant material throughout, e.g., rubber or suitable thermoplastic, and has a crown portion 12 which is, in a state of repose, substantially larger than the wearer's head so as to offer a loose floppy fit thereon.

The crown portion terminates in a marginal edge portion 13, diameter of which is such as to require that it

be stretched to fit around the wearer's head. As seen in FIG. 2 the crown portion is relatively thin and the marginal edge portion is thickened by an encircling tension strap 14. The tension strap 14 is rubber or other suitable elastic material and can be secured to the crown portion by a suitable adhesive. It will be understood that the crown portion and the tension strap can also be molded as an integral unit.

An inflatable tube 15 extends around and is secured to the marginal edge portion inside the cap. The tube 15 is formed of a thin strip of rubber or other suitable elastic material which is secured at its marginal edges 16-16 by a suitable means such as a rubber adhesive. The tube 15 can also be incorporated integrally with the cap during moulding.

A first filler tube 17 extends through the tension strap and marginal edge portion of the cap and opens into the tube 15. The filler tube 17 has an integral flange 18 which is adhesively secured to the tension strap 14.

A second filler tube 19 extends through the crown portion of the cap adjacent the filler tube 17 and is secured to the crown portion in the same manner as the filler tube 17 is secured. The tubes 17 and 19 are located one above the other or in close proximity and are of a length so that when the cap is fitted over the wearer's head they can reach the wearer's mouth so that air can be blown into the crown portion of the cap and into the tube 15. Both tubes 17 and 19 can be closed by conventional plugs 21-21.

OPERATION

In use, the bathing cap is fitted over the wearer's head with the marginal edge portion low enough to cover the hair. The wearer can then inflate the tube 15 sufficiently to effect an air tight seal and then inflate the crown. The tubes 17 and 19 can then be plugged and are then tied in a decorative knot. The knot also closes the tubes to prevent loss of air should the plugs 17-17 loosen.

The tension strip 14, it is seen, provides sufficient constrictive force to effect a tight grip of the marginal edge portion about the head while the inflated tube conforms to skull anomalies so as, not only to provide an effective water and air seal but to serve as a cushion to obviate possible discomfort of the constricting lower marginal edge of the cap.

It is to be understood that only enough air is blown into the crown portion of the cap to inflate it sufficiently so that it rides clear of the hair. Very slight positive pressure is required due to the thinness of the material of the crown portion thus preventing the cap from lifting off the head. The slight positive pressure however of the air trapped between the wearer's head and the cap crown portion further enhances the water seal effected by the inflatable tube 15.

Furthermore, although the filler tubes are functional in nature they also serve a decorative purpose as they can be tied into a decorative knot to resemble a flower or the like.

I claim:

1. An inflatable bathing cap including:
  - a. an inflatable crown portion formed of a pliant resilient material and being of a size, when in a state of repose, substantially larger than the wearer's head,
  - b. an elastic marginal edge portion adapted to have a snug fit around wearer's head,

- c. an elastic tension strap encircling the cap exteriorally of the marginal edge portion to effect a snug fit of the marginal edge portion about the wearer's head,
- d. an elastic inflatable tube extending around the 5 marginal edge portion inside the cap,
- e. a first air filler tube extending through the marginal edge portion into the inflatable tube,
- f. a second air filler tube extending into the inflatable crown portion of the cap,

10

- g. the first and second filler tubes being of sufficient length to reach the wearer's mouth when the cap is placed on the head so that air can be blown by mouth into the inflatable tube and into the inflatable crown portion of the cap and being disposed closely adjacent to one another so as to enable them to be tied into a knot so as to prevent escape of air.
